CLAIM

The ornamental design for a disposable spoon, as shown and described.

DESCRIPTION

FIG. 1 is a perspective view of my new design showing a disposable spoon;

FIG. 2 is another perspective view of my new design showing a disposable spoon;

FIG. 3 is a top plan view of FIG. 1;

FIG. 4 is a bottom plan view of FIG. 1;

FIG. 5 is a side elevation view of FIG. 1, the other side being a mirror image;

FIG. 6 is an enlarged elevation view of VI in FIG. 1;

FIG. 7 is an enlarged cross section taken along VII-VII in FIG. 3; and,

FIG. 8 is an enlarged cross section taken along VIII-VIII in FIG. 3.

The short dash-long dash broken lines in FIGS. 1 and 6, designating the boundary of the enlarged view, form no part of the claimed design.
